DIGITAL WRIST WATCH

Eugene Joseph Sulek, Richardson, Tex., assignor to
Texas Instruments Incorporated

Filed Aug. 29, 1974, Ser. No. 501,549

Term of patent 14 years

Int. Cl. D10—02

U.S. Cl. D10—38

Fig. 2

Fig. 1

Fig. 5

Fig. 3

Fig. 6

Fig. 4

FIG. 1 is a top, right perspective view of a digital wrist watch showing an embodiment of my new design;
FIG. 2 is a top plan view thereof;
FIG. 3 is a top end elevational view thereof;
FIG. 4 is a right side elevational view thereof;
FIG. 5 is a left side elevational view thereof;
FIG. 6 is a bottom plan view thereof;
FIG. 7 is a top, right perspective view of another embodiment of my new design of FIG. 1; and
FIG. 8 is a top plan view thereof, all other views being substantially identical to FIGS. 3-6, respectively.

I claim:

The ornamental design for a digital wrist watch, substantially as shown and described.
